UNITED STATES PATENT OFFICE.

HOLT NICHOLS, OF RUPERT, IDAHO.

MANIFOLD HEATER.

1,426,592.

Specification of Letters Patent. Patented Aug. 22, 1922.

Application filed January 25, 1921. Serial No. 439,841.

To all whom it may concern:

Be it known that I, HOLT NICHOLS, a citizen of the United States, residing at Rupert, in the county of Minidoka and State of Idaho, have invented certain new and useful Improvements in Manifold Heaters, of which the following is a specification.

This invention relates to improvements in manifold heaters for internal combustion engines.

An important object of the invention is the provision of a manifold heater which will heat the intake manifold, in such manner, as to effectively vaporize gasoline prior to its entry into the cylinders of the motor.

A further object of the invention is the provision of a manifold heater including an auxiliary heating device for heating the intake manifold in cold weather, in such manner that a low grade of gasoline can readily be vaporized.

A further object of the invention is the provision of a manifold heating device, which incloses the intake pipe, and thus prevents cooling effect of the fan, thereby aiding the vaporization of the gas therein, in such manner, as to produce regular explosions in the cylinders, thus preventing vibration of the engine.

Other advantages will be apparent during the course of the following detailed description.

In the accompanying drawings forming a part of this specification and in which like reference characters designate like parts throughout the same,

Figure 1 is a side elevation of a "Ford" internal combustion engine having the improved manifold heater attached thereto.

Figure 2 is an enlarged front elevation of the manifold heater.

Fig. 3 is a front elevation showing the casting of the manifold heater with the cover removed.

Fig. 4 is a horizontal cross sectional plan view taken through the manifold heater.

Fig. 5 is a vertical cross sectional view through the manifold heater showing the arrangement of parts therein.

Fig. 6 is a perspective view of the auxiliary heating element embodied in the manifold heater.

In the drawings wherein for the purpose of illustration is shown a preferred embodiment of my invention the letter A designates an internal combustion engine of the

"Ford" type; having an exhaust manifold B; and intake manifold C, thereon. The manifold heater D is preferably maintained in position upon the internal combustion engine to enclose the manifold B and C, by the manifold clamps E, which constitute a standard part of the "Ford" motor.

The manifold heater D comprises a casing 10 having apertures 11 and 12 in the back thereof adapted to fit over the two center glands of the exhaust manifold; and having apertures 13 and 14 in the back thereof, provided to fit over the two glands of the intake manifold. The face or front of the casing 10 is preferably open. The brackets 16 are positioned upon the floor 17 of the casing, such as by electric welding, or the like to detachably receive the burners G. A lid 18 is provided having overturned flanges 19 thereon to cover the open face of the casing 10. The lid 18 has the apertures 20 and 21 therein in such position that when the lid 18 is assembled upon the casing 10, they will be directly in front of the burners G, and from which the burners G can secure the proper supply of oxygen. Doors 22 and 23 are provided upon the lid 18, and pivotally attached thereto as by rivets 24 in such manner that they can be adjusted to regulate the area of opening of the aperture 21 communicating with the interior of the manifold heater G. A knob 25 is carried by the doors to facilitate swinging upon their pivot 24, and it is to be noted in this connection that the frictional contact of the doors 22 and 23 with the face of the cover 18 is sufficient to hold the doors 22 and 23 in an adjusted position.

The burners G comprise a metallic box 95 portion 26 filled with asbestos wool 27; and covered by wire gauze 28. The asbestos wool is adapted to be saturated with denatured alcohol, or gasoline for the purpose of igniting the same to provide an auxiliary 100 heater.

In order to attach the improved manifold heater to an internal combustion engine, remove the exhaust and intake manifolds, by removing the clamps E. The casing 10 is then slipped over the glands of the exhaust and intake manifolds in such manner that the two center glands of the exhaust manifold are positioned within the apertures 11 and 12 of the casing, and the two end glands 11 of the intake manifold are positioned within the apertures 13 and 14 in the casing 10. It

is to be noted that the bolts of the glands E are inserted through apertures 30 in the back of the casing 10. The lid 18 is then placed upon the casing 10, in a position that 5 the apertures 20 and 21 are directly in front of the burners G, and in such manner, that apertures 31 therein receive the bolts of clamp E. The clamp members E are then tightened upon the lid 18 until the same is 10 firmly positioned upon the casing 10.

Ordinarily the heat from the exhaust manifold is sufficient to heat the intake manifold in the interior of the manifold heater, and in such manner that the device 15 will function properly.

However, if the weather is severely cold the auxiliary heaters G are ignited through the apertures 20 and 21, and the doors 22 and 23 positioned in such manner that sufficient 20 oxygen will reach the burners as to permit operation. Since all parts of the manifold heater D are protected from the currents of air from the fan F, the device could be used upon an automobile, and the 25 burners would still function correctly.

It is to be understood that the form of my invention herein shown and described is to be taken as the preferred example of the same, and that various changes in the shape 30 size, and arrangement of parts may be resorted to without departing from the spirit of the invention and scope of the sub-joined claims.

I claim:

35 1. In a manifold heater, the combination, with an internal combustion engine having exhaust and intake manifolds, of a casing enclosing said intake manifold and a portion of the exhaust manifold, auxiliary 40 burners positioned within the casing for heating the intake manifold, a detachable lid for the front of said casing to permit access to the burners, said lid having apertures therein adjacent the detachable burners, and adjustable doors mounted upon said 45 lid for regulation of the opening into said casing.

2. In a manifold heater, the combination,

with a "Ford" internal combustion engine, having exhaust and intake manifolds, and 50 clamps therefor, of a casing having apertures therein to fit over the glands of said manifolds in order to position the manifolds inside thereof, said casing maintained in position upon said "Ford" engine by the 55 manifold clamps.

3. In a manifold heater, the combination, with a "Ford" internal combustion engine, having exhaust and intake manifolds, and 60 clamps therefor, of a casing having apertures therein to fit over the glands of said manifolds in order to position the manifolds inside thereof, and a detachable lid for the face thereof, said lid and casing being maintained in position upon said "Ford" engine 65 by the manifold clamps, and doors pivotally mounted upon said lid whereby access may be had to the interior of the casing.

4. In a manifold heater, the combination, with a "Ford" internal combustion engine, 70 having exhaust and intake manifolds, and clamps therefor, of a casing having apertures therein to fit over the glands of said manifolds in order to position the manifolds inside thereof to protect the same from cooling 75 effect of the fan, and detachable burners positioned within said casing, said casing being maintained in position upon said "Ford" engine by the manifold clamps.

5. In a manifold heater, the combination 80 with a "Ford" internal combustion engine including exhaust and intake manifolds and a clamp therefor, of a casing including 85 a rectangular shaped body portion for disposition to entirely receive the intake manifold and a portion of the exhaust manifold, said body portion having apertures therein adapted to fit over the glands of said manifolds, detachable burners positioned in said body portion upon both sides of said intake 90 manifold, and therebeneath, and a detachable lid for disposition upon said rectangular body casing to entirely enclose the intake manifold and a portion of the exhaust manifold therein.

HOLT NICHOLS.
